UNITED STATES PATENT OFFICE.

NATHANIEL WARSHAW, OF MATTAPAN, MASSACHUSETTS, ASSIGNOR TO LEWIS-SHEPARD COMPANY, OF WATERTOWN, MASSACHUSETTS, A CORPORATION OF MASSACHUSETTS.

ELEVATING TRUCK.

Application filed August 15, 1927. Serial No. 212,925.

This invention relates to improvements in single-lift elevating trucks in which the load-supporting means is raised and lowered by vertically-swinging movements of the steering tongue.

In usual single-lift elevating trucks of this type detachable interengaging means are provided, respectively, upon the load-supporting means and upon the tongue which, in order to be engaged and disengaged, require that the tongue shall be in substantial alignment with the longitudinal axis of the truck. Frequently it is desirable to raise or lower the load-supporting means when, by reason of a narrow aisle or some obstruction, it is impossible to bring the tongue into substantial alignment with the longitudinal axis of the truck. The object of the present invention is to provide a construction in which the load-supporting means may be elevated by the vertical swinging movement of the tongue when the latter is in any usual steering position.

The usual steering positions of the tongue relative to the longitudinal axis of the truck seldom require a divergence of more than thirty degrees on either side of the longitudinal axis of the truck, and the mechanism illustrated herein shows suitable interengaging means upon the load-supporting means and tongue which are capable of being engaged in any position within the limits specified. It will be readily understood, however, that the interengaging member of the tongue may be so constructed as to provide a much wider range of lateral movement of the tongue if desirable.

A further object of the invention is to provide a single-lift elevating truck with interengaging means, respectively, upon the load-supporting means and tongue which may be engaged by the depression of the tongue when in any normal steering position and in which the interengaging member upon the load-supporting means will be positioned when the load-supporting means is elevated to engage the co-operating member upon the tongue upon depression of the tongue without manipulation of any special mechanism to cause such engagement.

A further object of the invention is to provide means for withholding the interengaging member of the load-supporting means from engaging position when the load-sup-

porting means is lowered, with manually operable means for causing engagement of said members when the load-supporting means is in lowered position.

These and further objects and features of the invention will more fully appear in the following description and accompanying drawings and will be particularly pointed out in the claims.

In the drawings, Fig. 1 is a perspective view of a single-lift elevating truck embodying the present invention;

Fig. 2 is a plan view of the same, the tongue being shown in vertical position and in section to permit a clearer view of the interengaging member of the tongue;

Fig. 3 is a detail side elevation of the lower portion of the tongue and the engaging member thereof; and

Fig. 4 is a rear elevation of a portion of the tongue and the engaging member thereof.

Fig. 5 is a view, partially in elevation and partially in vertical section, of an elevating truck embodying the invention, parts of the frame and platform being broken away to permit illustration of both ends of the truck;

Fig. 6 is a detail view showing the manner in which a lifting hook is mounted upon the platform;

Fig. 7 is a detail view illustrating the manner in which the end of the tongue having the lifting member thereupon is mounted upon the steering post.

This invention comprises certain improvements in single-lift elevating trucks disclosed in Patent No. 1,434,016, granted October 31, 1922 to Lewis Shepard Company, assignee of Ralph M. Lovejoy, and the general construction of the truck shown in the drawings is substantially identical with that illustrated in said patent. It will, however, be understood that the present invention is applicable to various other types of single-lift elevating trucks within the spirit and scope of the claims.

The elevating truck illustrated in the drawings herein comprises a head 1 which may be a casting having a flat body portion with an upwardly extending cylindrical boss 2 and downwardly-extending end flanges 3 to which side bars 4 are connected. The side bars 4 are provided at their rear ends with brackets 5 having bosses 6 to receive the rear axle 7 of the truck wheels 8 rotatably mounted

upon the axle 7 upon the outside of the side bars 4 and secured upon the axle in any suitable manner. Preferably roller bearings are employed for the rear axles, as is usual in 5 trucks of this character adapted to transport heavy loads. The front end of the truck is provided with suitable steering mechanism which, as illustrated, comprises a pair of steering wheels 9 which are journaled in the 10 lower end of a yoke 10 having a vertical steering post 11 journaled centrally in the cylindrical boss 2. The upper end of the steering post 11 is provided with a preferably integral bracket having upwardly-extending ears 12, 15 which support a shaft 13 upon which the base portion 14 of a tongue 15 is pivotally mounted to swing vertically. The base portion 14 of the tongue has secured to it and preferably integral therewith an arcuate lifting member 20 16 which is adapted to be interengaged with a complementary lifting member in the form of a hook, which is flexibly connected to the load-supporting means, as will hereinafter more fully appear. The lifting member 16 preferably is oval in cross section, to give maximum strength, and also to present a curved surface to be engaged by the hook of the load-supporting means.

The load-supporting means is in the form 30 of a platform comprising side bars 17 which are connected together at their rear ends by an inverted angle bar 18, the end of the side bars 17 desirably having extensions 19 which wrap around the ends and rear walls of the 35 angle bar 18. The rear end of the platform is supported by a link 20, which may be of skeleton form, pivoted upon the rear axle 7 of the truck. In the preferred construction illustrated, the link 20 is provided at either end 40 with bosses 21, 22 which are rotatably mounted upon the axle and are located, respectively, inside and outside of the bosses 5 of the side bars 4. The upper end of the link 20 is curved in cross section and lies within the angle of 45 the angle bar cross-girder 18, in a manner disclosed in prior Patent No. 1,434,016 aforesaid. The side bars of the load-supporting means are desirably connected by a central girder 23 and are also connected together at the 50 front ends by a transverse girder having a horizontal portion 24 which is secured to the front ends of the side bars 17 and an integral vertical wall 25 forming a dash-board. The wall 25 is provided with a series of forwardly-extending brackets 26 which are spaced apart and in which a shaft 27 is mounted. Links 28 arranged in substantial parallelism with the link 20 at the rear end of the truck are pivotally mounted upon the shaft 27 on 55 the front end of the load-supporting means and at their lower ends are pivotally mounted upon shafts 29 which are carried by the side bars 4 of the truck. The co-operating engaging member upon the load-supporting 60 means is in the form of a hook 30 adapted

to engage the member 16. The lower end of the hook is provided with laterally-extending brackets 31 having downwardly-extending ears which are pivotally mounted upon the shaft 27. 70

Inasmuch as the lifting member 16 of the tongue is of arcuate form concentric with the axis of the steering post, the hook 30 may be engaged by the member 16 when the steering tongue is in any steering position. The length 75 of the hook 30 and the leverage of the member 16 are such that when engaged and the tongue depressed the load-supporting means will be moved forwardly relatively to the frame and steering mechanism of the truck. 80 Such forward movement will swing the links 20 and 28 toward a vertical position, thereby raising the load-supporting means. By raising the tongue the links 20 and 28 will be permitted to swing downwardly so that the platform will be restored to its lowered position. 85

Any suitable means may be provided for locking the load-supporting means in elevated position. The particular construction 90 herein is similar to that illustrated in Patent No. 1,434,016 above mentioned, and comprises a hook 32 which is pivotally mounted upon a shaft 33 in suitable bosses on the head 1 and is provided with an extension in which a 95 stud shaft 34 is mounted, with the counter-weight 35 pivoted upon said stud shaft and adapted, when in the position illustrated in Fig. 2, normally to raise the hook 32 so that its hooked end 36 will engage the shaft 27 when the load-supporting means is moved to its forward and elevated position. The counter-weight 35 is provided with an extension 37 which has a stud 38 extending into a slot 39 in an arm 40 which is also pivotally connected to the load-supporting means. The slot 39 is of such length that when the load-supporting means is in elevated position the counter-weight 35 may be reversed so that its weight 100 will rest upon the hook and tend to release the hook when the load-supporting means is slightly elevated, as more fully described 105 in the prior patent aforesaid. 110

Preferably means are provided for normally holding the hook 30 out of position to engage the member 16 of the tongue when the load-supporting means is in lowered position. This construction likewise may be similar to that disclosed in the prior patent aforesaid 115 and comprises a hook-positioning member which is in the form of a link 41 which is pivotally mounted upon an ear 42 extending upwardly from one of the brackets 31 of the hook and located a considerable distance from the shaft 27 upon which the hook 30 is pivoted. The link 41 has a downwardly-extending foot 43 which, when the load-supporting means is in elevated position, engages one of the ears of the bracket 31 and limits the movement of the hook in a manner hereinafter de- 120 125 130

scribed so that its curved end is retained in the path of the elevating member 16 of the tongue. The other end of the link 41 is provided with a slot 44 which is engaged by a 5 stud upon a bell-crank lever 45 which is mounted on a shaft 46 carried by the head 1. The bell-crank lever 45 is provided with a pedal 45^x, and the slot 44 is so proportioned that the bell-crank lever may be operated by 10 the pedal to draw the link 41 forwardly and thereby force the hook into engagement with the lifting member 16 of the tongue when the platform is in lowered position. A spring 47 connected at one end to link 41 and at its opposite end to an ear on the hook bracket 31 and quite closely adjacent to the shaft 27 tends normally to force the link endwise in a direction toward the load-supporting means, thereby causing the hook to be carried into a 20 vertical position when the load-supporting means is lowered.

As the load-supporting means is raised and advanced during its elevating movement, the link 41 is pivotally moved about the stud on 25 the bell-crank lever 45, and when it is in substantially its elevated position the foot 43 of the link engages one of the downwardly-extending lugs of the hook bracket 31, thus limiting the endwise movement of the link and 30 retaining the hook in raised position to permit free steering movement of the tongue and also in a position to be engaged by the lifting member 16 upon depression of the tongue when it is desired to lower the load-supporting means from elevated position. Consequently the hook-positioning means acts to prevent the hook from falling forwardly into the path of the lifting member 16 of the tongue when the load-supporting means is in 35 40 its lowered position, and also serves, when the load-supporting means is in elevated position, to retain the hook in proper position to be engaged by the lifting member 16 of the tongue upon the downwardly-swinging movement of the tongue, thereby avoiding the necessity of any manually-operable device for causing engagement of the hook 30 with the lifting member 16 of the tongue when the load-supporting means is in elevated position.

By reason of the fact, therefore, that the lifting member 16 of the tongue is of arcuate form concentric with the axis of the steering post, interengagement of the hook 30 and lifting member 16 may be effected when the load-supporting means is in lowered position and the tongue in any usual steering position by the depression of the pedal 45^x to draw the link forward and thereby lock the hook 30 50 into engagement with the lifting member 16 so that the load-supporting means can be elevated by depression of the tongue when the tongue is in any usual steering position. Depression of the tongue 16 will then raise the load-supporting means to elevated position,

in which it will be held by the hook 32, as heretofore described. When the tongue is raised to usual steering position the lifting member 16 thereof will lie below the point of the hook 30 and will permit the tongue to be 70 swung through an arc of 180 degrees or more, so that the truck can be steered freely in any direction. When it is desired to lower the load-supporting means, depression of the tongue will cause the lifting member 16 thereof to engage the hook 30, and further depression of the tongue will then raise the load-supporting means sufficiently to enable the hook 32 to drop out of engagement with the shaft and permit the load to be lowered. 75

By virtue of the present invention, therefore, the load-supporting means can be raised and lowered by the vertical swinging movement of the tongue without the necessity of bringing the tongue into substantial alignment with the central longitudinal axis of the truck, thus enabling the load-supporting means to be operated when the tongue extends into a narrow aisle or is prevented by some obstruction from being swung into alignment 90 with the longitudinal axis of the truck. Furthermore, the ability to raise and lower the load-supporting means with the tongue in any usual steering position saves considerable effort and time of the user as compared with that required for manipulation of usual types of single-lift trucks. 95

It will be understood that the particular embodiment of the invention claimed is of an illustrative character and is not restrictive 100 of the scope of the claims and that the invention may be embodied in other types of trucks to which it may be applicable within the meaning of the claims.

Having thus described the invention, what 105 is claimed as new, and desired to be secured by Letters Patent, is:

1. In an elevating truck comprising load-supporting means and steering mechanism having a tongue pivotally mounted to swing vertically, means including a member flexibly connected to said load-supporting means, and rigid co-operating means upon said tongue operable by vertical swinging movements of the tongue when in any usual steering position to raise and lower said load-supporting means.

2. In an elevating truck comprising load-supporting means and steering mechanism having a tongue pivotally mounted to swing vertically, means including a member flexibly connected to said load-supporting means, and a co-operating member rigid with said tongue operable by vertically swinging movements of the tongue when in any usual steering position to raise and lower said load-supporting means.

3. In an elevating truck comprising load-supporting means and steering mechanism having a steering post and a tongue pivotally

mounted thereon to swing vertically, means including a hooked member pivotally connected to said load-supporting means, and a co-operating arcuate member on said tongue substantially concentric with the axis of the steering post adapted to be engaged by said hooked member when the tongue is in any usual steering position and operable by vertical swinging movements of the tongue when so engaged to raise and lower the load-supporting means.

4. In an elevating truck comprising load-supporting means and steering mechanism having a steering post and a tongue pivotally mounted thereon to swing vertically, means including a hooked member pivotally connected to said load-supporting means, and a co-operating arcuate member oval in cross section, rigid with said tongue, substantially concentric with the axis of the steering post adapted to be engaged by said hooked member when the tongue is in any usual steering position and operable by vertical swinging movements of the tongue when so engaged to raise and lower the load-supporting means.

5. In an elevating truck comprising load-supporting means and steering mechanism having a steering post, a tongue mounted thereon to swing vertically, an arcuate lifting member on said tongue substantially concentric with the axis of the steering post, a co-operating hook pivotally mounted on said load-supporting means tending normally to engage the lifting member of said tongue, and automatic means acting upon said hook to withhold the same from engagement with said arcuate lifting member when the load-supporting means is in lowered position and to permit engagement of the hook therewith when the load-supporting means is in elevated position with the tongue in any usual steering position.

6. In an elevating truck comprising load-supporting means and steering mechanism

having a steering post, a tongue mounted thereon to swing vertically, an arcuate lifting member on said tongue substantially concentric with the axis of the steering post, a co-operating hook pivotally mounted on said load-supporting means tending normally to engage the lifting member of said tongue, automatic means acting upon said hook to withhold the same from engagement with said arcuate lifting member when the load-supporting means is in lowered position and to permit engagement of the hook therewith when the load-supporting means is in elevated position with the tongue in any usual steering position.

7. In an elevating truck comprising a wheel supporting frame having steering mechanism including a steering post, a tongue mounted on said steering post to swing vertically, load-supporting means movable longitudinally relatively to said frame, means for elevating and lowering said load-supporting means upon such relative movement thereof, an arcuate lifting member on said tongue substantially concentric with the axis of the steering post, a hook pivotally mounted on the front end of said load-supporting means and positioned to lie in the path of said arcuate member when the load-supporting means is in elevated position and to be engaged thereby upon depression of the tongue when in any usual steering position, and means operable when the load-supporting means is in lowered position to remove and retain said hook out of engagement with said arcuate lifting member, whereby the tongue will be free for steering purposes.

In testimony whereof, I have signed my name to this specification.

NATHANIEL WARSHAW.
